CALF WEANER

Filed Dec. 23, 1922

E. R. Ruppert.

WITNESS:

J. E. Newsom
INVENTOR
BY Victor J. Evans
ATTORNEY

UNITED STATES PATENT OFFICE.

JOHN E. NEWSUM, OF DACOMA, OKLAHOMA.

CALF WEANER.

Application filed December 23, 1922. Serial No. 608,694.

To all whom it may concern:

Be it known that I, JOHN E. NEWSUM, a citizen of the United States, residing at Dacomia, in the county of Woods and State of Oklahoma, have invented new and useful Improvements in Calf Weaners, of which the following is a specification.

My present invention has reference to a calf and colt weaner, and has for its object 10 to produce a simple, durable and reliable means for holding the closure member of the device in closed position when the calf or colt raises its head to nurse but which is moved to open position when the calf or colt grazes.

To the attainment of the foregoing and other objects which will present themselves as the nature of the invention is better understood, reference is to be had to the drawing 20 which accompanies and which forms part of this application.

In the drawing:—

Figure 1 is a view illustrating my improved weaner as the same appears when a calf places its muzzle to the ground.

Figure 2 is a similar view showing the weaner when the calf lifts its head to attempt to nurse.

Figure 3 is an approximately central vertical longitudinal sectional view through the improvement.

Figure 4 is a perspective view of the basket-like closure member.

As disclosed by the drawing, I make use 35 of a nose band 1 which fits around the nose and jaws of the calf. This nose band is constructed of metal and has attached to the sides thereof the head stall 2. The head stall is, of course, in the nature of leather straps, one of which being provided with the usual buckle and the other having spaced openings to receive the tongue of the buckle therethrough.

To the sides, near the front end of the 45 nose band 1 I pivot links 3. Each link is offset adjacent to its outer end, the said offset portions being pivoted, as at 4 to the straight sides 5 adjacent to the front of the closure member 6. By reference to the 50 drawings it will be noted that the upper edges of the sides 5 of the closure member are struck at a curvature, from the center thereof to the ends 7. The ends are inwardly inclined and are integrally formed with 55 the angle walls 9 of the bottom of the clo-

sure member. The bottom at or adjacent to its center is provided with spurs 10 designed to prick the cow should the calf attempt nursing. The angle walls of the bottom 9 are provided with series of apertures 11 60 whereby the calf or colt may freely breathe when the closure is automatically swung to closed position.

The basket-like closure 9 is wholly constructed of metal, and incident to the links 65 pivotally attached beyond the center of the said closure beyond the center of the nose band 1, the portion of the closure to the rear of the said pivots is weightier than that at the forward end thereof. The result 70

is that the closure will swing to closed position when the calf or colt raises its head and incident to the angle end and bottom of the closure the latter will swing to open position when brought to contact with the 75

ground on the lowering of the head of the calf or colt when grazing. It will be further noted, by reference to Figure 3 of the drawings that the lower forward end of the metal nose band is received in and may contact with the outer angle end 7 of the closure, while the opposite end thereof has its edge in contact with the lower or outer edge of the nose band adjacent to the rear thereof. Of course, the nose band is of a size to 80 permit of this arrangement without interfering with the comfort of the animal upon which the device is applied, but such contacting engagement renders positive the operation of the improvement.

Having described the invention, I claim:—

A weaner of the character described comprising a nose band, means for retaining said nose band upon an animal, links bent outwardly intermediate their ends and having 95 their inner ends secured upon opposite sides of the nose band, a closure member for the outer end of the nose band and being secured thereto through the medium of connection with the outer ends of the links, said closure member being spiked and provided with curved portions providing the side walls thereof and the walls adjoining the curved walls being substantially V-shaped in cross section for cooperative association with the spikes to cause the closure to swing to inoperative position when one of these parts engages the ground.

In testimony whereof I affix my signature.
JOHN E. NEWSUM.
